UNITED STATES PATENT OFFICE.

JOSEPH LYNCH, OF DUMONT, NEW JERSEY, ASSIGNOR TO LYNCH BRENNAN INC., OF NEW YORK, N. Y., A CORPORATION OF NEW YORK.

FRAME.

1,253,847.

Specification of Letters Patent. Patented Jan. 15, 1918.

Application filed January 22, 1917. Serial No. 143,608.

To all whom it may concern:

Be it known that I, JOSEPH LYNCH, a citizen of the United States, and a resident of Dumont, in the county of Bergen and State 5 of New Jersey, have invented a new and Improved Frame, of which the following is a full, clear, and exact description.

My invention relates to metallic frames and has reference more particularly to built-up frames. The object of the invention is to provide a simple, inexpensive, and strong frame structure which can be built up rapidly to any desired size.

With the above and other objects in view, 15 the nature of which will more fully appear as the description proceeds, the invention consists in the novel construction, combination and arrangement of parts as herein fully described, illustrated and claimed.

20 In the accompanying drawings, forming part of the application, similar characters of reference indicate corresponding parts in all the views.

Figure 1 is a perspective view of a frame 25 embodying my invention;

Fig. 2 is a vertical cross section on line 2—2, Figure 1;

Fig. 3 is a horizontal cross section on line 3—3, Fig. 1;

30 Fig. 4 is a cross section through the bottom member of the frame on line 4—4, Fig. 1;

Fig. 5 is a bottom-up perspective view of a lower corner of the frame; and

35 Fig. 6 is a perspective view of a modified structure of a frame of which one corner is shown.

In the manufacture of metallic frames of the channeled type it is customary to keep 40 standard sizes of frames made up in stock, and when an order is given for a frame of larger or smaller size than the standard ones the delivery cannot be made until a certain time, that is, the time necessary to make up 45 the frames. In most frames of this type the corner is soldered to the channeled member and the work requires considerable time.

The object of my invention is to provide 50 frame in which there is a driving fit between the channeled members and the corners of the frame. By keeping in stock various lengths of channeled members, any size of frame can be quickly built up and delivery made within 24 hours. Furthermore,

frames already in stock can be easily taken 55 apart and remodeled for frames of different sizes at comparatively little expense and labor.

The frame comprises a channeled bottom member 7 which is driven into horizontal 60 arms 8 of corners 9 provided at the ends thereof. These corners 9 are each made from a blank into a channel-shaped corner by a method well known in the art. One of the arms of such a corner has the bottom 65 of the channel open longitudinally, as shown at 10. The opening is in the arm 8 and, consequently, the arm 8 is weaker than the arm 11 of the same corner.

The sides of the arms 8 and 11 are folded 70 inwardly, as shown at 12, so as to engage the inner surface of the channeled members. For example, the arms 8, by engaging with their infolding portions 12 the channeled member 7, considerably strengthen said 75 arms, which would otherwise have a tendency to open due to the longitudinal opening 10 in the bottom thereof. The side channel members 13 have also a driving fit into the arms 11 of the corner 9. The upper 80 corners 14 are similar to the corners 9 when the frame has for its upper member a channeled member, but in cases where the frame is to be used for cards, the upper corner members 14 are slightly different.

85 The arm 15 of each corner is exactly similar to the arm 11 of the corner 9; but the normally longitudinal open arm 16 differs from the arm 8 of the corner 9 in that it has infolded portions not only at the 90 inner edges of the arm but at the outer edges also, as shown at 17. These infolded portions 17 provide the necessary passage for the card into the side channel members 13, and also serve as an additional grip for 95 the corner with the flat bars 18 which bind the arms 16 of the upper corners 14. The thickness of the bars 18 is substantially that of the thickness of the sides of the channeled members 7 and 13, and their width that of 100 the width of the side of a channeled member.

When the frame is to be used with cards, the bottom channeled member 7 is provided with a bearing 19 for a support. This bearing 105 is in the shape of a channeled member the sides of which are infolded at the longitudinal edges to form a driving fit with the

bottom member 7. It has a depending socket 20 for engaging a standard, or it may have a standard for engaging a socket.

In the modified structure shown in Fig. 5 6 the channeled members are shown to be tubular. The driving fit is obtained in a similar way by infolding the longitudinal edges of the tubular corner at the openings, as clearly shown in Fig. 6.

10 From the above description it will be seen that all that is necessary is to keep in stock corners as described and standard lengths of channeled members, and when an order for such frames is received they can 15 be assembled very rapidly. In cases where an odd size of frame is required, special lengths of channeled members may be cut, the same corners being used in connection therewith. No soldering or riveting is necessary, and the normally weak open arms 20 of the corners are strengthened when they are driven on to the channeled members, as previously explained.

I claim:

25 1. A frame of the class described comprising channel-shaped corner members having one arm thereof open longitudinally at the bottom, said corners having infolded side portions at the longitudinal edges of 30 the arms, and channel-shaped members having a driving fit with the arms of the corners and adapted to be engaged with their sides between the sides and the infolded portion of the corners of the arms, whereby 35 the open arm of the corner is reinforced.

2. A frame of the class described com-

prising a channeled bottom member, channeled side members, channeled corners binding the side members to the bottom members, said corners presenting inwardly folded side portions for engaging the sides of the channeled bottom and side members, a pair of flat bars forming the top member of the frame, and corners binding the side members to the bars, said corners having inwardly folded side portions at the inner and outer edges for engaging each bar, substantially as and for the purpose set forth.

3. A frame of the class described comprising a channeled bottom member, channeled side members, channeled corners binding the side members to the bottom members, said corners presenting inwardly-folded side portions for engaging the sides of the channeled bottom and side members so 55 that a driving fit is formed between the corners and the channeled members, a channel-shaped bearing having infolded sides at the longitudinal edges and having a driving fit on the channeled-bottom members, said bearing having means for engaging a standard from which the frame is to be supported, a pair of flat bars forming the top member of the frame, and channel-shaped corners binding the side members to the bars, 60 said corners having inwardly-folded side portions at the inner and outer edges for engaging each bar and presenting an opening to provide entrance for a card to the side channeled members.

JOSEPH LYNCH.
